UNITED STATES PATENT OFFICE.

JAY P. WALKER, OF OKLAHOMA CITY, OKLAHOMA, ASSIGNOR TO AMERICAN TANK COMPANY, OF OKLAHOMA CITY, OKLAHOMA, A CORPORATION OF OKLAHOMA.

ANTIFREEZE FLUID CONTROL FOR STORAGE TANKS.

Application filed July 17, 1925. Serial No. 44,250.

This invention relates to new and useful improvements in anti-freeze fluid control for storage tanks.

This invention has to do with the storage of fluids which congeal when subjected to temperatures below the point of freezing, such as crude oil from petroleum fields. In such cases it is the practice to install steam coils in the bottom of the tank to heat the liquid so that it will flow. Where pressure and vacuum regulators are installed outside the tank, which is common practice, they frequently freeze and when the tank is heated, such regulators do not thaw out. The result is usually a damaged tank owing to the vapor pressure which is built up in the tank when the liquid is heated, the tank either bulging or collapsing. Further if the liquid feed valve is mounted outside the tank it would also freeze.

The object of the invention is to provide controlling means for relieving the pressure and vacuum within the tank arranged so as to become operative when the liquid in the tank is heated.

A further object of the invention is to provide means within the tank for automatically controlling the level of the liquid in the tank and also for maintaining an air space at the top of the tank.

Frequently the hot vapors escaping from a heated tank ignite and cause a fire, therefore another object of my invention is to provide an arrester for extinguishing a fire at the end of the vapor escape pipe.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a view of a storage tank constructed in accordance with my invention, a portion of the tank shown in section,

Fig. 2 is a vertical sectional view of the inlet valve,

Fig. 3 is a cross-sectional view taken on the line 3—3 of Fig. 2; and

Fig. 4 is a detail of the fire arrester.

In the drawings the numeral 10 designates an ordinary storage tank which may be of any approved construction. The tank has a manhole 11 at the center of its top, which

latter may be crowned. The manhole is closed by a cover 12. An outlet pipe 13 leads from the side of tank near its bottom.

A central vertical relief pipe 14 has its upper end terminating at the manhole and below the cover 12. The lower end of the pipe 14 is connected by an elbow 15 with a horizontal pipe 16, extending through the side of the tank. The pipe 16 is near the bottom of the tank. In the pipe 16 near the elbow or at any other suitable place within the tank is connected a combination pressure and vacuum regulator 17, which may be of any suitable construction for the purpose, such regulators being well known and now in common use in this art. A drain cock 18 is connected in the pipe 16 outside the tank for drawing off the condensation.

The pipe 14 is open at its upper end so that vapors and gases trapped in the upper end of the tank may escape into the pipe 14. The regulator 17 is set to permit fluid at a predetermined pressure to pass and also to relieve a vacuum in the tank. In order that the liquid flowing into the tank from the fluid pipe 19 may be cut off at a level below the top of the pipe 14 and not flow into the latter, I provide an automatic cut-off valve comprising a casing 20 (Figs. 2 and 3) and located within the tank just under the top thereof. The casing depends from a cover flange 21 which is fastened on the down-turned end of the pipe 19. In the lower end of the casing is an annular valve seat 22. A guard disk 23 is supported on legs 24 above the seat and below the end of the pipe.

A valve 25 under the guard engages on the seat 22 and has a depending stem 26. A lever 27 pivoted at 28 in a housing 29 is pivoted to the valve stem, but has its greater length extending outwardly from the pivot 28. A float 30 is mounted on the outer end of the lever. The guard protects the valve from the impact of the liquid flowing into the casing from the pipe 19. When the liquid rises to its high level the float 30 will be raised and the valve 25 will be closed, thus cutting off the supply to the tank. The invention is not to be limited to the cut-off valve shown as many forms of cut-off valves located in the tank could be used for the same purpose.

The pipe 16 is extended through a dyke 31 and connected by an elbow 32 to an upright pipe 33. The pipe 33 is connected at

its upper end to a short horizontal pipe 34 by an elbow 35. An arm 36 depending from the pipe 34 is welded or otherwise secured thereto. A lever 37 (Fig. 4) is pivoted intermediate its ends on the lower end of the arm. A cap 39 is provided with ears 38 between which one end portion of the lever is connected; while a chain 40 is connected to the other end of the lever. Normally the lever is swung to a horizontal position and the end of the pipe 34 is open.

In cold climates it is necessary to thaw out such liquids as crude oil and this is usually done by placing a steam coil in the tank particularly at the bottom. I have not illustrated the coil in the drawings because the means used to heat the liquid has nothing to do with the invention. When the liquid is heated the regulator 17 and the valve casing 20 will also be heated and if frozen, will be thawed out. It has been the practice to locate the regulator outside the tank and frequently the regulator was frozen.

It will be seen that the heating of the liquid, crude oil, will cause the generation of vapors or gases at the upper end of the tank which will build up a pressure unless relieved. If the pressure regulator is frozen such a pressure would damage the tank or if the vacuum regulator was frozen the tank would be collapsed when the liquid was pumped out.

By my arrangement the liquid will be held at the high level by the float 30 and below the entrance to the pipe 14. Vapors or gases accumulating in the upper portion of the tank will pass out through the pipes 14, 16, 33, and 34; or a vacuum will be relieved by the same conductor. If the escaping vapors or gases should ignite it is merely necessary to pull the chain 40 to swing the lever 37 and close the end of the pipe 34 by the cap 39; the arrester thus extinguishing the fire.

Various changes in the size and shape of the different parts, as well as modifications and alterations may be made within the scope of the appended claims.

What I claim is:

- 50 1. The system of controlling fluids in a heated storage tank which consists in automatically cutting off the supply of liquid at a high level to create a vapor space in the tank conducting the vapors from said space by conducting the same through a regulator immersed in the heated liquid in the tank, and by relieving a vacuum in said tank through a regulator immersed in the heated liquid.
- 60 2. In an anti-freeze control for storage tanks, the combination with a storage tank, of an automatic feed for the liquid within the tank, a relief pipe extending from a point above the liquid level in the tank down to the bottom portion of the tank and out

through the side of the tank, and pressure and vacuum regulator connected in said pipe within and near the bottom of the tank.

3. In an anti-freeze control for storage tanks, the combination with a storage tank, of an automatic feed for the liquid within the tank, a relief pipe extending from a point above the liquid level in the tank down to the bottom portion of the tank and out through the side of the tank, pressure and vacuum regulator connected in said pipe within and near the bottom of the tank, and a fire arrester on the end of the pipe outside of and remote from the tank.

4. In an anti-freeze control for heated storage tanks, means for maintaining a vapor space in the tank above the liquid and a conductor leading from the said space through the liquid in the tank, and a pressure regulator connected in said conductor and located in the lower portion of the tank.

5. In an anti-freeze control for heated storage tanks, means for maintaining a vapor space in the tank above the liquid, a conductor leading from the said space through the liquid in the tank, and a pressure and vacuum regulator connected in said conductor and located in the lower portion of the tank.

6. In an anti-freeze control for heated storage tanks, a liquid feed pipe entering the top of the tank, an automatic cut-off valve on the feed pipe within the upper portion of the tank, an upright relief pipe in the tank having its upper end above the high level of the liquid, a second pipe connected to the relief pipe near the bottom of the tank and extending through the side of the tank, and a pressure and vacuum regulator connected in the second pipe within the tank.

7. In an anti-freeze control for heated storage tanks, a liquid feed pipe entering the top of the tank, an automatic cut-off valve on the feed pipe within the upper portion of the tank, an upright relief pipe in the tank having its upper end above the high level of the liquid, a second pipe connected to the relief pipe near the bottom of the tank and extending through the side of the tank, and a pressure and vacuum regulator connected in the second pipe within the tank.

8. In an anti-freeze control for heated storage tanks, a liquid feed pipe entering the tank, an upright relief pipe open at its upper end and extending from a point near the top of the tank to the bottom of said tank and directed outwardly through said tank, and a pressure and vacuum regulator adjacent the bottom of the tank.

In testimony whereof I affix my signature.

JAY P. WALKER.
